US00D497185S1

(12) **United States Design Patent** (10) Patent No.: **US D497,185 S**
Gaska et al. (45) Date of Patent: **** Oct. 12, 2004**

(54) **WRITING IMPLEMENT CONTAINER**

(75) Inventors: **Gilius A. Gaska**, Madison, WI (US);
Christa R. Walter, Lake Mills, WI (US)

(73) Assignee: **Berol Corporation**, Freeport, IL (US)

(**) Term: **14 Years**

(21) Appl. No.: **29/156,381**

(22) Filed: **Feb. 28, 2002**

(51) LOC (7) Cl. **19-06**

(52) U.S. Cl. **D19/85; D19/77**

(58) Field of Search **D19/35, 36, 65, D19/75, 77, 78, 81-85, 95, 99, 100; 206/214, 224, 371; 211/69.1-69.9, 163; D9/455; D7/557, 641**

(57) **CLAIM**

We claim the ornamental design for a writing implement container, as shown and described.

DESCRIPTION

FIG. 1 is a top, right front perspective view of a writing implement container showing our new design;

FIG. 2 is a front elevational view thereof;

FIG. 3 is a top plan view thereof;

FIG. 4 is a right side elevational view thereof; and,

FIG. 5 is a bottom plan view thereof.

The ornamental design which is claimed is shown in solid lines in the drawings. The broken lines in the drawings are for illustrative purposes only and form no part of the claimed design.
